UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 11,989, dated October 26, 1880.

Application filed July 31, 1880. Term of patent 3½ years.

To all whom it may concern:

Be it known that I, EDUARD LEISSNER, of New York, in the county and State of New York, have invented a new and original Design for Wall-Paper, of which the following is a specification.

This invention relates to a new and original design for wall-paper and similar fabrics.

It consists in a novel grouping and configuration of figures hereinafter more fully described.

The accompanying photograph illustrates a face view of wall-paper having my new design.

By three vertical or longitudinal stripes, *a*, *b*, and *d*, the paper is divided into four upright parallel sections, *A*, *B*, *C*, and *D*.

The section *A* is, by three cross-stripes, *e*, *f*, and *g*, divided into three shorter fields, *h*, (between *e* and *f*), *i*, (between *f* and *g*), and *j*, (between *g* and *e*.) The field *h* contains an ornamentation, consisting of a bouquet of buds and flowers with long stems, which come near together at the bottom of the field. The field *i* contains an ornamentation of star-shaped flowers and small buds upon a branching vine. The field *j* contains an ornamentation of round flowers with prominent radiating pistils and their buds growing upon a branch or vine.

The section *B* is divided by four cross-stripes, *l m n o*, into the fields *p*, *q*, and *j'*. The field *j'* is identical in its ornamentation with the field *j*, already described. The field *p* is ornamented with a bouquet of flowers, which bears a great resemblance to the bouquet in the field *h*, but differs from it in arrangement. The field *q* is ornamented with flowers upon a vine, much like those shown in the field *i*, but differing somewhat in arrangement.

The section *C* is divided by three cross-stripes, *s t u*, into the fields *p' q' r*. The fields *p'* and *q'* are identical in their ornamentation with the fields *p* and *q*, already described. The field *r* is ornamented with flowers and buds like those shown in the fields *j* and *j'*, but differing somewhat in their arrangement.

The section *D* is divided by four cross-stripes, *v w x y*, into the field *h'*, identical in its ornamentation with the field *h*, the field *i'*, nearly

identical in its ornamentation with the field *i*, and the field *r'*, identical in its ornamentation 50 with the field *r*.

With the longitudinal stripe *a* is entwined the band *E E E*, crossing in front of and behind it alternately and passing under the cross-stripes *g f e* and over the cross-stripes *l m n o*. 55 A similar band, *G G G*, is entwined in the same manner with the longitudinal stripe *b*, and passes under the cross-stripes *l m n o* and over the cross-stripes *s t u*. A similar band, *H H H*, is entwined in the same manner with 60 the longitudinal stripe *d*, and passes under the cross-stripes *s t u* and over the cross-stripes *v w x y*. The effect produced is that of a lattice-work trellis with rectangular openings, in which appear flowering bouquets or branches 65 with flowers thereupon.

I claim—

1. The design for wall-paper, consisting of the trellis-like figure composed of longitudinal stripes *a b*, cross-stripes *l m*, and entwining 70 stripes *E E* and *G G*, substantially as shown.
2. The design for wall-paper, consisting of the group *i*, composed of vine, buds, and flowers, substantially as shown.
3. The design for wall-paper, consisting of 75 the group *h*, composed of a bouquet of flowers, substantially as shown.

4. The design for wall-paper, consisting of the group *j*, composed of buds and flowers upon a spreading branch, substantially as shown. 80

5. The design for wall-paper, consisting of the section *A*, composed of groups *h i j*, cross-stripes *g f e*, and side stripe, *a*, substantially as shown.

6. The design for wall-paper, consisting of 85 the section *B*, composed of groups *p j'*, of cross-stripes *l m n o*, and side stripes, *E* and *G*, substantially as shown.

7. The design for wall-paper, consisting of the section *C*, composed of groups *g' p' r*, of cross-stripes *s t u*, and side stripes, *G* and *H*, substantially as shown. 90

8. The design for wall-paper, consisting of the section *D*, composed of groups *h' i' r'*, cross-stripes *v w x y*, and side stripe, *H H*, substantially as shown. 95

9. The design for wall-paper, consisting of the sections A and B, substantially as shown.

10. The design for wall-paper, consisting of the sections A, B, and C, substantially as shown.

11. The design for wall-paper, consisting of the sections A B C D, substantially as shown.

12. The design for wall-paper, consisting of the sections A B C D and interlacing stripes E G H, substantially as shown.

EDUARD LEISSNER.
